UNITED STATES PATENT OFFICE.

EDWARD EARL SENSENBACK AND GEORGE KURTZ KOCHER, JR., OF WHITE HAVEN,
PENNSYLVANIA.

GARMENT.

Application filed January 23, 1925. Serial No. 4,283.

This invention relates to garments and particularly to union under-garments or suits and has for an object to provide an improved construction wherein by the design, 5 the cloth cut away for forming the legs may be used to form the gussets.

Another object of the invention is to provide what is known as a union under-garment of substantially the usual appearance but with the lower and the upper part of 10 the leg sections so designed and cut that the part removed from the lower sections may be connected to the upper sections for forming gussets.

15 In the accompanying drawings—

Figure 1 is a perspective view of a figure with a garment embodying the invention applied thereto.

Figure 2 is a partial rear view of the figure and garment shown in Figure 1.

Figure 3 is a partial rear view of the lower part of the figure with one of the legs bent showing certain features of the invention.

Figure 4 is a vertical sectional view 25 through the central part of the garment shown in Figure 1, the same being on a somewhat enlarged scale.

Figure 5 is a bottom plan view of the structure shown in Figure 4.

30 Figure 6 is a plan view of the garment immediately after the same has been cut out.

Figure 7 is a plan view of the garment shown in Figure 1 with the parts spread out and the cut-away portions of the legs removed.

Figure 8 is a plan view spread out of one 35 of the cut-away portions of the lower part of the legs as shown in Figure 6.

Figure 9 is a sectional view through Figure 6, on line 9—9.

Heretofore in forming union garments of the character shown in the accompanying drawings, it was customary to cut out the same from the desired pattern and then cut 45 from a separate piece of cloth suitable gussets for enlarging and properly fitting the seat portion of the garment. In the present structure, the use of goods from a separate piece of cloth is not necessary and yet the 50 same enlarged gusset structure for the seat is provided.

As indicated in Figure 6, the garment is made from a tubular piece of goods 1 and is slit at 2 and 3 for forming the two seat sections 4 and 5. The garment is also cut at

points 6 and 7 as well as slit at points 8 and 9 to form the upper part. The structure indicated from numbers 6 to 9 is old and well known and, therefore, will not be particularly set forth. However, in forming the 60 leg sections 10 and 11, the cloth while still in the tubular form as shown in Figure 6, is cut along compound curve lines 12 and 13 whereby sections 14 and 15 are provided, said sections being, of course, double. When either of these sections is spread out, it will appear as shown in Figure 8. In forming the section as shown in Figure 8, a very small portion 16 is removed from each of the members 14 and 15.

In securing the parts together, the leg sections 10 and 11 are folded and stitched together so that the edges 17 and 18 of each leg will be connected together from the bottom to near the respective points 19 and 20. 70 Between the points 19 and 21 on each leg, the ends 22 of the respective sections 14 and 15 are secured by suitable lines of stitching and then the adjacent edges of these sections are secured together by a line of stitching 23. 75 The opposite edges of the respective sections 14 and 15 are connected by lines of stitching 24 and 25 to the respective seat sections 4 and 5 as indicated particularly in Figures 2 and 3. This will enlarge the seat 80 section at the back and between the legs in order to give the desired fit and fullness across the hips. It will also be noted that this arrangement of gusset does not interfere with the free opening and closing of 85 the seat section in the usual manner.

In forming the complete seat section, the body 1 is slit at 26 and 27. It will thus be noted that in forming a garment according to the present invention that not only are 90 the two pieces 14 and 15 cut to shape from the legs 10 and 11 and afterwards joined together to make the gusset of the proper size and dimension to make a full size gusset but also in cutting these two pieces from the 100 leg by the particular desired showing, the proper amount of goods is left in the leg and also leaves it in the proper shape and size to be seamed.

What we claim is:

1. The method of constructing a union undergarment of the character described, comprising taking a length of flattened tubular fabric including a body and leg portions, cutting equal area and similar shaped ta- 110

pered pieces from the opposite edges of the leg portions to form similar gusset sections, disposing said gusset sections edge to edge and sewing such edges together to form a central seam, sewing together the edges of the leg portions, slitting the back of the body portion to form two drop-seat sections, sewing the free edges of the sectional gusset to the inner edges of the drop-seat sections, and into the inner leg openings, the gusset sections being symmetrically disposed with respect to the vertical axis of the body.

2. The method of constructing a union undergarment of the character described from a length of tubular fabric, and including a body and pair of leg portions, comprising the cutting of two tapered gusset sections of the same dimensions and shape, the opposite edges of said sections defining a

compound curve and the bases a straight line, 20 said gusset sections having a length substantially equal to the extent of the legs, sewing together the edges formed by cutting out the aforesaid gusset sections to constitute the legs, slitting the tube up the center of the back a predetermined distance and providing shorter parallel slits at each side of the center slit, then slitting the back across the upper ends of all the parallel slits, to form drop-seat sections, inserting the sectional 30 gusset in the opening formed by the aforesaid slits and sewing the side edges thereof to the inner leg portions and the edges of the drop-seat sections, to complete the drop-seat, enlarge the garment at the hip portions and form a closed crotch.

GEORGE KURTZ KOCHER, JR.
EDWARD EARL SENSENBACH.
